(57) **CLAIM**

The ornamental design for the cord organizer, as shown and described.

DESCRIPTION

FIG. 1 is a front view of the cord organizer in accordance with an embodiment of the present invention.

FIG. 2 is a rear view of the cord organizer of FIG. 1.

FIG. 3 is a perspective view of the cord organizer of FIG. 1.

FIG. 4 is a front view of the cord organizer in accordance with an alternative embodiment of the present invention.

FIG. 5 is a rear view of the cord organizer of FIG. 4; and,

FIG. 6 is a perspective view of the cord organizer of FIG. 4.

The broken lines shown in the drawing represent the portions of the cord organizer in the second embodiment that form no part of the design for which protection is claimed herein.

1 Claim, 6 Drawing Sheets

FIG. 1

FIG. 2

FIG. 3

FIG. 4

FIG. 5

FIG. 6
